The Union Switch & Signal Company, Swiss-
vale, Pa., a corporation of Pennsylvania

Application April 8, 1942, Serial No. 438,107

8 Claims. (Cl. 200—80)

My invention relates to speed responsive devices, and particularly to governors which are adapted for use on trains in connection with automatic train control equipment to limit the speed at which the trains may operate under certain conditions.

One object of my invention is to provide a governor of the type described in which the effect of centrifugal force on the contact parts is reduced to a minimum.

Another object of my invention is to provide a governor of the type described in which the contact opens and closes with a reliable snap action.

Governors embodying my invention are an improvement upon those described and claimed in Letters Patent of the United States No. 2,113,645 granted to me on April 12, 1938.

According to one form of my invention, a pair of interconnected centrifuge members are pivotally mounted on a supporting member which is rotated at a speed which is proportional to the speed of the vehicle or other device with which the governor is connected. The centrifuge members are disposed for swinging movement toward and away from the axis of rotation of the supporting member to "in" and "out" positions, and are biased to their "in" positions by spring link assemblies arranged to provide a limited toggle action which causes the centrifuge members to swing all the way from either extreme position to the other when they start to move. A contact finger is attached at one end to the one centrifuge member and is provided at the other end with a low resistance contact button which cooperates with a similar button mounted on a fixed arm secured to a slip ring forming part of the supporting member. For the purpose of eliminating the effect of centrifugal force on the contact finger, the finger is secured to the associated centrifuge member in such a position that it is disposed substantially on the radial line extending from the axis of rotation of the centrifuge member through the axis of rotation of the supporting member, and the contact button carried thereby is disposed substantially at the axis of rotation of the centrifuge assembly. External connections with the contact members are made through the medium of said slip ring and another slip ring which is electrically connected with said contact finger and which is insulated from said first mentioned slip ring.

According to another form of my invention the centrifuge members are biased to their "in" positions by springs which apply a force to the

members along a line extending parallel to the line passing through their pivots; and the centrifuge members each have their center of gravity disposed on a line located closer to the axis of rotation of the governor than a line normal to the line passing through the pivots, whereby the centrifugal moment exerted on the members increases rapidly as they move from their "in" to their "out" positions.

10 Other objects and characteristic features of my invention will become apparent as the description proceeds.

I shall describe two forms of speed responsive devices embodying my invention, and shall then 15 point out the novel features thereof in claims.

In the accompanying drawings, Fig. 1 is an end view showing one form of governor embodying 20 my invention. Fig. 2 is a side view of the governor shown in Fig. 1 as it appears when viewed from the right in Fig. 1, with some of the parts broken away or sectioned to better illustrate the construction of the remaining parts. Fig. 3 is an 25 isometric view of one of the centrifuge members forming part of the governor shown in the preceding views. Fig. 4 is a view similar to Fig. 1 showing a modification of the governor illustrated in Fig. 1.

Similar reference characters refer to similar parts in each of the several views.

30 Referring first to Figs. 1 to 3, inclusive, the device in the form here shown comprises a head made up of two annular conducting members 1 and 2 clamped by means of bolts 3 to the opposite sides of an insulating plate 4, which plate, in turn, is secured by means of bolts 5 to a flange 6 formed on one end of a drive shaft 7. The drive shaft 7 is operatively connected with the device to the speeds of which it is desired to have the governor respond, and when this device is a railway vehicle, the drive shaft may be connected with one of the vehicle axles by means of drive mechanism similar to that shown and described in an application for Letters Patent of the United States, Serial No. 373,132, filed by myself and another on January 4, 1941, for Generator and mounting means therefor. As will appear hereinafter, the outer surfaces of the annular conducting members 1 and 2 serve as slip rings, and it is therefore necessary that these members should be insulated from each other. To this end, the member 1 is insulated from the bolts 3 by means of insulating sleeves 9 and insulating washers 8.

50 Mounted in bushed bearings 10 and 11 provided in the member 2 at the opposite ends of the base

of an isosceles triangle the apex of which is disposed at the axis of rotation of the governor head are two pivot pins 12 and 13 which pivotally support two centrifuge members 14 and 15 (see the pivot pin 13 shown in Fig. 2). These centrifuge members as here shown are each in the form of a crank, and each is provided with a straight arm (14a, 15a) and with a weight arm so disposed that the center of gravity of the weight arm is located on a line extending through the pivotal axis of the member at right angles to the longitudinal axis of the straight arm. The ends of the straight arms 14a and 15a are connected together by a toothed connection 16 which constrains the two centrifuge members to operate in unison, and the parts are so proportioned that gravitational and vibrational forces will balance out.

Associated with each centrifuge member is a spring link assembly which acts to oppose the movement of the centrifuge members under the action of centrifugal force. These spring link assemblies are similar, and each comprises a spring rod 20 slidably mounted at one end in a guide 22 screwed into an outwardly projecting lug 23 formed on the annular member 2. The other end of each spring rod 20 is provided with a semi-spherical head 24 which fits into a semispherical recess 25 formed in the weight arm of the associated centrifuge member, whereby the spring rods are rendered self aligning in all directions with respect to the associated weight arm. Each spring link assembly also comprises a compressed coil spring 26 which bears at one end against an annular flange 27 provided on the headed end of the associated spring rod, and at the other end against an annular shoulder 28 provided on the associated guide 22.

The centrifuge members operate a contact comprising two cooperating contact buttons 30 and 31. The contact button 30 is secured to a rigid arm 32 formed on the annular member 1, whereby this contact button is electrically connected with the annular member 1. The other contact button 31 (see Fig. 3) is secured to a flexible contact finger 33 attached by means of an angle bracket 34 to the weight arm 14b of the centrifuge member 14, which latter is electrically connected with the annular member 2 by means of a flexible connector 35. As was pointed out hereinbefore, the outer surfaces of the annular members 1 and 2 serve as slip rings, and it will be seen, therefore, that external electrical connections with the governor contact may be readily made by providing suitable brushes (not shown) which bear against the slip rings.

The free end of the contact finger 33 is bent to form a U-shaped return bend 33a which extends between bifurcations 14c (see Fig. 3) provided on a rigid finger 14d formed on the weight arm 14b of the centrifuge member 14. The finger 33 is biased by its own resiliency to such a position that it will swing clear of the finger 14d to the extent permitted by the return bend when the centrifuge members swing outwardly under the action of centrifugal force, and it will be seen, therefore, that the return bend 33a acts as a stop to limit the motion of the finger when the governor contact opens. It will also be seen that the finger 14d acts as a stop to limit the motion of the centrifuge members toward the axis of rotation of the governor head under the action of the toggle spring.

The motion of the centrifuge members away from the axis of rotation of the governor head under the action of centrifugal force is limited by stop screws 36 mounted in the lugs 23. The stop screws are adjustable and are arranged to be locked in their adjusted positions by jam nuts 36.

For convenience I shall hereinafter refer to the positions of the centrifuge members to which they are biased by the toggle link assemblies as "in" positions and the opposite positions as "out" positions.

The spring link assemblies are so positioned that when the weight arms occupy their "in" positions, the force applied by each spring link assembly will be applied along a line which makes an obtuse angle with the line on which the center of gravity of the weight arm is located. With the spring link assemblies arranged in this manner, when the centrifuge members swing outwardly, a limited toggle action takes place which causes the resultant spring force applied to the centrifuge members to decrease, whereby when the critical speed is reached at which the centrifuge members start to move from their "in" to their "out" positions, they will move all of the way with a snap action without further change in speed. Similarly, when the critical speed is reached at which the centrifuge members start to move from their out to their in positions, they will move all of the way to their in positions with a snap action. It will be apparent, of course, that the obtuse angle formed between the line of force of the spring link assembly and the line extending through the axis of rotation of the centrifuge members and on which the center of gravity is located should never be great enough to cause the resulting toggle to reach its dead center position when the centrifuge members are swung to their "out" positions.

It is desirable in a governor of the type described to be able to cause the governor to respond to any critical speed within a wide range of speeds, such for example, as a range between 45 and 100 miles per hour, merely by selecting springs 26 having different characteristics. To be able to accomplish this result, it is necessary to eliminate any effect of centrifugal force on the contact parts, and in accordance with my present invention I accomplish this result by disposing the flexible contact finger 33 so that it lies substantially on the radial line extending between the axis of rotation of the governor head and the axis of rotation of the associated centrifuge member, and I attach the contact button 31 to this finger in such a position that it is disposed substantially at the axis of rotation of the governor head. This arrangement eliminates any necessity for changing the tension of the contact spring when the springs 26 are changed to cause the governor to operate at different speeds.

The operation, as a whole, of the governor will be apparent from an inspection of the drawing and from the foregoing description without the necessity for further detailed description, it being obvious that the contact 30-31 will be opened or closed according as the centrifuge members 14 and 15 occupy their "out" or their "in" positions, and that when the contact opens or closes, it will do so with a snap action.

It will also be obvious that since the contact finger 33 is biased away from the finger 14d in the manner previously described, when the centrifuge members are moving from their "in"

to their "out" positions, the contact 30-31 will not open until the arm 14b has moved far enough to cause the finger 14d to engage the return bend 33a. This construction insures that the contact will not open in response to slight movements of the centrifuge members caused by vibration, or while the contact members are in their unstable conditions which they occupy when the governor is operating at very close to the critical speed and thereby avoids chattering of the contacts.

Referring now to Fig. 5, the governor here shown differs from that shown in the preceding view in the construction by virtue of which snap action of the contacts is obtained. As here shown, the centrifuge members which are here designated 50 and 51 are so constructed that their centers of gravity, instead of being located on lines extending through the pivots at right angles to the straight arms, as is the case with the centrifuge members 14 and 15 shown in Figs. 1 and 2, are located on lines drawn through the pivots closer to the axis of rotation of the governor than the first mentioned lines. In other words, the center of gravity of the centrifuge member 50 instead of being located on dash line T is located on dash line T1.

Furthermore, as here shown, the centrifuge members are biased to their in positions by compression springs 52 and 53 positioned at their outer ends by spring guides 54 and 55 screwed through threaded openings in the lugs 23, and held in place at their inner ends by spring guides 56 and 57 provided on the centrifuge members 50 and 51, respectively. The springs are so disposed that the lines of the spring forces extend substantially parallel to the line drawn through the pivots. The remainder of the governor shown in Fig. 5 is similar in all respects to the governor shown in Figs. 1 and 2.

The object of this modified construction is to provide a considerably increased centrifugal moment when the centrifuge members move from their "in" to their "out" positions without the necessity for resorting to spring link assemblies of the toggle type such as those shown in Fig. 1. For example, the moment arm of the centrifugal force acting on the centrifuge member 50 when this member occupies its "in" position is distance Y which is at right angles to a line drawn between the center of rotation of the centrifuge assembly and the center of gravity Z of the centrifuge member 50. The centrifugal moment is the centrifugal force acting at Z times its moment arm Y. When the centrifuge members move out under the action of centrifugal force, the center of gravity of centrifuge member 50 moves to a point Z1 which gives a moment arm Y1 which it will be noted is considerably larger than the moment arm Y. There is also some actual increase in the value of the centrifugal force because the radial distance of the center of gravity from the center of rotation has also increased. By proper proportioning of the parts the increase in centrifugal moment as the centrifuge members move out can be made considerably greater than the increase in the spring force exerted by the springs 52 and 53, and therefore a snap action of the contact can be obtained.

This arrangement has the disadvantage that it is affected slightly by gravity and vibration because the center of gravity is not located so that these forces will balance out. However, it can be satisfactorily employed in high speed gov-

ernors because the effects of gravity and vibration at high speeds are small compared with the centrifugal force.

Although I have herein shown and described only two forms of speed responsive devices embodying my invention, it is understood that various changes and modifications may be made therein within the scope of the appended claims without departing from the spirit and scope of my invention.

Having thus described my invention, what I claim is:

1. A speed responsive device comprising a rotatable supporting element, a centrifuge member 15 pivotally supported on said supporting element for movement toward and away from the axis of rotation of said supporting element, and a contact finger secured to said centrifuge member and carrying a contact button which cooperates with a fixed contact button mounted on said supporting element to form a contact, said contact finger being disposed substantially on the radial line extending from the axis of rotation of said supporting element to the pivotal axis of said centrifuge member and the button carried by said finger being disposed substantially at the axis of rotation of said supporting element to eliminate the effect of centrifugal force on the contact parts.

2. A governor comprising a centrifuge member pivotally mounted on a rotatable supporting element, and contact mechanism operated by said centrifuge member and comprising a contact spring secured to the centrifuge member and disposed substantially on the radial line extending from the axis of rotation of said supporting member through the pivotal axis of said centrifuge member, said contact spring being provided with a contact button disposed substantially at the axis of rotation of the supporting member and cooperating with a fixed contact button mounted on the supporting member.

3. A governor comprising a rotatable supporting member, two centrifuge members pivotally mounted on said supporting member at the opposite ends of the base of an isosceles triangle the apex of which is disposed at the axis of rotation of said supporting member, each said centrifuge member comprising a straight arm and a weight arm having a center of gravity disposed on a line extending through the pivot substantially at right angles to the straight arm, said weight arms being movable toward and away from the axis of rotation of the supporting member to "in" and "out" positions and said straight arms being interconnected to cause the two centrifuge members to operate in unison, the parts being so proportioned that gravitational and vibrational forces balance out, two spring link assemblies one operatively connected with each weight arm for biasing the weight arms to their "in" positions, said links assemblies being disposed to apply a force to the weight arms along a line extending at an obtuse angle to the line on which the center of gravity is located, whereby a limited toggle action is provided which causes the weight arms to swing between their "in" and "out" positions with a snap action, a contact finger secured to one weight arm and disposed substantially on the radial line extending from the axis of rotation of said supporting member through the pivotal axis of the associated centrifuge member, and a contact button secured to said finger substantially at the axis of rotation of the supporting member and cooperating with

a fixed contact element mounted on the supporting member to form a contact.

4. A governor comprising an insulating plate secured to a driving member, two annular conducting members secured to said insulating plate, a spring biased centrifuge member pivotally attached to the one annular conducting member and provided with a contact finger disposed substantially on the radial line extending from the axis of rotation of said plate through the pivotal axis of said centrifuge member, said finger being electrically connected with the one annular conducting member, and a contact button secured to said finger substantially at the axis of rotation of said plate and cooperating with a fixed contact button mounted on a rigid arm formed on the other annular member, said two annular members serving as slip rings to facilitate making external electrical connection with the contact formed by said two contact buttons.

5. A governor comprising a centrifuge member pivotally mounted on rotatable supporting means, said centrifuge member being movable to "in" and "out" positions and being biased to its "in" position in such manner that it will move between its "in" and "out" positions with a snap action, a contact finger secured to said centrifuge member and disposed substantially on the radial line extending from the axis of rotation of said supporting means through the pivotal axis of said centrifuge member, a contact button secured to said finger substantially at the axis of rotation of said supporting means and cooperating with a fixed contact button mounted on the supporting means to form a contact, a rigid finger formed on said centrifuge member and cooperating with said contact finger at the side opposite to the contact button to determine the "in" position of the centrifuge member, said rigid finger being provided with a bifurcated end and said contact finger being provided with a return bend which extends between the bifurcations on said rigid finger, said contact finger being biased away from said rigid finger by its own resiliency to a position determined by said return bend.

6. A governor comprising a rotatable supporting means, two centrifuge members pivotally supported on said supporting means at the opposite ends of the base of an isosceles triangle the apex of which is disposed at the axis of rotation of said supporting means, each said centrifuge member comprising a straight arm and a weight arm, said straight arms being connected together to cause the centrifuge members to operate in unison, said weight arms being movable toward and away from the axis of rotation of said supporting means to "in" and "out" positions, spring means associated with the weight arms and effective to bias them to their "in" positions by a force acting on a line extending substantially

parallel to the straight arms, a contact finger secured to one weight arm and disposed along the line extending from the axis of rotation of the supporting means to the pivotal axis of the associated centrifuge members, and a contact button secured to said finger substantially at the pivotal axis of said supporting means and cooperating with a fixed contact button secured to the supporting means to form a contact, said centrifuge members being so constructed that their centers of gravity are located on lines extending through their pivots closer to the axis of rotation of the supporting means than the lines extending through their pivots at right angles to the straight arms, whereby the centrifugal moment increases as the arms move outwardly to provide a snap action of the contact.

7. A governor comprising a centrifuge member pivotally mounted on a rotatable supporting element and including a weight arm rotatable toward and away from the axis of rotation of said supporting element, a contact operated by said centrifuge member, and spring means associated with said weight arm and effective to bias said weight arm toward the axis of rotation of said supporting element by a force acting normal to a line extending through the pivotal axis of said centrifuge member farther from the axis of rotation of said supporting member than the line passing through the center of gravity of said weight arm and the axis of said centrifuge member, whereby the centrifugal moment increases as the weight arm moves outwardly to provide a snap action of said contact.

8. A governor comprising a rotatable supporting means, two centrifuge members pivotally supported on said supporting means at the opposite ends of the base of an isosceles triangle the apex of which is disposed at the axis of rotation of said supporting means, each said centrifuge member comprising a straight arm and a weight arm, said straight arms being connected together to cause the centrifuge members to operate in unison, said weight arms being movable toward

and away from the axis of rotation of said supporting means to "in" and "out" positions, spring means associated with the weight arms and effective to bias them to their "in" positions by a force acting on a line extending substantially parallel to the straight arms, and a contact operated by said centrifuge members, said centrifuge members being so constructed that their centers of gravity are located on lines extending through their pivots closer to the axis of rotation of the supporting means than the lines extending through their pivots at right angles to the straight arms, whereby the centrifugal moment increases as the arms move outwardly to provide a snap action of the contact.

60 HERBERT L. BONE.
